Robt. D. Kitchel.

UNITED STATES PATENT OFFICE.

FRANCIS I. DU PONT, OF WILMINGTON, DELAWARE.

MEANS FOR OBSERVING THE INTERIORS OF FIRE-BOXES OF AUTOMOBILE STEAM-GENERATORS.

1,285,650.

Specification of Letters Patent.

Patented Nov. 26, 1918.

Application filed February 26, 1917. Serial No. 151,067.

To all whom it may concern:

Be it known that I, FRANCIS I. DU PONT, a citizen of the United States, residing at Wilmington, county of New Castle, and 5 State of Delaware, have invented a new and useful Improvement in Means for Observing the Interiors of Fire-Boxes of Automobile Steam-Generators, of which the following is a full, clear, and exact description, 10 reference being had to the accompanying drawings, which form a part of this specification.

In the operation of steam driven automobiles it is important to maintain the boiler 15 within a fairly definite temperature range and more particularly to maintain the fuel ignited. Owing to the necessity of locating the boiler within a closed chamber and below the level of the eye of the operator, no 20 satisfactory means has been evolved whereby the operator can, while driving, at any time readily apprise himself of the condition of the fire which heats the boiler. To secure such information, the 25 driver must first stop the car, alight, and then make the examination. Ordinarily, in the event that the flame is extinguished, the driver is unaware of the condition until after the boiler has cooled down substan- 30 tially below the range of normal efficiency, and time is lost, and further cooling occurs, in reigniting, and further time is lost until the boiler is restored to normal efficiency. It is obvious that if means were afforded to 35 enable the driver to instantly, at any moment, apprise himself of conditions within the fire-box of the boiler, much delay and annoyance would be saved. It is the object of my invention to provide means whereby 40 at all times the flame within the fire-box may be readily observed without the necessity of the driver stopping the car or moving from his seat.

A preferred embodiment of the invention 45 is shown in the drawings, wherein:—

Figure 1 is a view, in elevation, of a steam boiler and observation means.

Fig. 2 is a section on the line 2—2 of Fig. 1.

Fig. 3 is a detail sectional view of the observation devices.

Fig. 4 is a perspective view of the same.

The boiler is located, as usual, within the hood *a* and is sheathed in a non-heat con-

ducting cover *b*. Between the tubes *c* and 55 grate *d* of the boiler is a coil of pipe *f* communicating with a supply pipe *e*, controlled by a valve *e'* and leading from a tank (not shown) containing liquid fuel, such as gasoline or kerosene. The coil of pipe *f* is pro- 60 longed outside the boiler, its extremity ex- tending into an orifice *g* in the fire-box wall beneath the grate. Located above the grate *d* is a small supplemental grate *h*, below 65 which extends the end of a relatively small pipe *i*. This pipe is formed into a small coil above grate *h* and thence extends outside the fire-box into communication with the main supply pipe *e* behind the valve *e'*. The liquid which is vaporized in pipe *i* is main- 70 tained constantly ignited and forms a pilot light for the ignition of the main supply of liquid fuel which is vaporized in pipe *f* whenever the same is admitted to the fire- 75 box by opening the valve *e'*.

There is nothing of patentable novelty in the construction above described and it will be understood that the construction of the boiler and its described appurtenances may be substantially modified without making 80 less applicable thereto the features of nov- elty embodying my invention, which will now be described.

Communicating with the rear of the fire- 85 box is a tubular member *m*, which prefer- ably extends horizontally, and, in the con- struction of boiler shown, on a level with the part of the fire box above the grate or burner, so that it will directly aline with the body of flame above the grate or burner. The rear of the tube *m* is flanged and be- 90 hind the tube is an open-topped box *n* which is similarly flanged and abuts against the rear of tube *m*, one of the abutting members being cut away, as shown in Figs. 3 and 4, 95 to permit of the insertion of a square of glass or other transparent medium *o*, which closes communication between the members *m* and *n*. Springs *p*, secured (say) to the front flanged end of member *n*, hold the 100 glass pressed against the rear flanged end of member *m*.

Arranged obliquely between the bottom and rear faces of the box *n* is a mirror *r*. The mirror preferably extends throughout 105 a height at least equal to the height of the interior of the tubular member *m* and is ar- ranged at such an angle that light rays

passing rearwardly will be deflected upwardly at an angle that will about meet the eye of the operator when sitting in a normal position. An inclined tube *s* is secured to, 5 and closes, the top of the box *n*, and is arranged at such an angle that its axis is parallel with the deflected rays of light.

It is quite obvious that by looking through the rear or upper end of tube *s*, the fire may 10 be seen by the driver at any time.

The glass *o* is arranged far enough from the fire to insure against breakage and to avoid the glass smoking too quickly. It is readily removable (to facilitate cleaning) 15 and replaceable.

Having now fully described my invention, what I desire to claim and protect by Letters Patent is:

1. The combination with a steam generator, of an outside tube connecting with an opening in the fire-box and extending away from the fire-box, a light transmitting medium closing said tube at a distance from the wall of the fire-box, and a light deflecting medium arranged behind the light transmitting medium.

2. The combination with a steam generator, of an outside tube connecting with an opening in the fire-box and extending 30 away from the fire-box, a light transmitting medium arranged in said tube to obstruct the escape of heated gases therethrough, and a light deflecting medium arranged behind the light transmitting 35 medium.

3. The combination with a steam generator, of a tubular structure connecting with an opening in the fire-box and extending away from the fire-box, a light transmitting medium, means on the tubular structure to removably hold said light transmitting medium in position to obstruct the escape of heated gases through the tube, and a light

deflecting medium arranged behind the light transmitting medium.

4. The combination with a steam generator, of a tubular structure connecting with an opening in the generator and extending toward the fire-box, a light transmitting medium, means on the tubular structure to 45 removably hold said light transmitting medium in position to obstruct the escape of heat through the tube, an upwardly inclined tube arranged behind the light transmitting medium and connected with the first 50 tube, and a light deflecting medium arranged at the junction of the two tubes and acting to deflect rays of light passing through the first tube and the light transmitting medium 55 through the second tube.

5. In a steam motor driven vehicle, the combination with the fire-box of a steam generator, of a bent sight tube extending from the fire-box, a light deflecting medium located in the bend of the tube, and a transparent closure within the tube between the light deflecting medium and the fire-box and closing the tube against the passage of air or flame.

6. In a steam motor driven vehicle, the combination with the fire-box of a steam generator, of a sight tube extending horizontally from an opening in the fire-box and thence inclined upwardly at an obtuse angle to the horizontal section, a light deflecting medium located at the junction of the two sections, and a transparent closure 70 within the horizontal section of the tube between the light deflecting medium and the fire-box and closing the tube against the 75 passage of air and flame.

In testimony of which invention I have hereunto set my hand at Wilmington, Delaware, on this 24th day of February, 1917.

FRANCIS I. DU PONT.
